UNITED STATES PATENT OFFICE.

WILLIAM H. GILLETTE, OF HARTFORD, CONNECTICUT.

TIME-STAMP.

SPECIFICATION forming part of Letters Patent No. 309,537, dated December 23, 1884.

Application filed December 5, 1883. (No model.)

To all whom it may concern:

Be it known that I, WILLIAM H. GILLETTE, a citizen of the United States, residing at Hartford, in the county of Hartford and State 5 of Connecticut, have invented a new and useful Improvement in Time-Stamp, of which the following description and claims constitute the specification, and which is illustrated by the accompanying drawings.

10 This is a time-stamp which stamps upon the upper side of papers Arabic or other characters approximately representing the time of day at which the papers stamped by it were respectively so stamped, and which 15 automatically changes those characters at stated intervals, so as to make them approximately correspond with exact current time, and which performs these functions by means of new devices and new combinations of devices and by a new mode of operation.

Figure 1 is an external perspective view of the apparatus. Fig. 2 is a central vertical longitudinal section thereof. Fig. 3 is a cross-section looking toward the left on line X X of 25 Fig. 2. Fig. 4 is a cross-section looking toward the left on line Y Y of Fig. 2. Fig. 5 is a cross-section looking to the right on line Z Z of Fig. 2. Fig. 6 is a side view looking toward the right of the spurred wheel T and the 30 wheel Q. Fig. 7 is a section on the line W W of Fig. 2. Fig. 8 is a view of the bottom of the stamp proper, showing one set of its automatically-changing figures in the center, and showing its manually-changed matter in 35 the border. Fig. 9 is a longitudinal central section of the shaft L and of the adjacent part of the shaft J, showing the manner in which the shaft L is mounted.

A is the fixed frame of the apparatus. It 40 has a hinged lid, B, which, when raised, gives access to the interior.

C is an oscillating frame, hung on the journals D D', which journals turn in bearings in the frame A, and which bearings are pierced 45 through the walls of the latter frame substantially at the points where the common tangents of the wheel Q and the gear I reach those walls. The frame C is also supported by the spiral springs E E'.

50 F is a shaft connected at the right of the indicated fracture with the arbor of a proper

chronometer. Keyed to that shaft are the gear G and the wheel H. The latter has a discontinuous flange extending toward the left from the border of its left-hand surface.

55

I is a gear keyed to the right-hand end of the shaft J. From the right-hand side of that gear three spurs, K K' K'', project horizontally.

L is a shaft turning in bearings in the frame A and in the axis of the shaft J.

M is a gear keyed to that shaft and identical in size and number of teeth with the gear G.

N is a spiral spring, one end of which is fastened to the gear M, and the other end of 65 which is fastened to the gear I.

O is a ratchet keyed to the shaft J.

P is a strong elastic blade, the larger end of which is rigidly fixed within a recess in the frame C.

70

Q is a wheel keyed to the shaft R. The right-hand part of the periphery of that wheel has teeth just double in number the teeth on the gear I, and the left-hand part of that periphery is plain throughout, except that it has 75 the recess S sunk therein directly toward the axis of the wheel. From the left-hand side of the wheel the spur Q' projects horizontally in substantially the position shown in Fig. 6.

T is a wheel keyed to the shaft U. It has 80 two sets of spurs of five spurs each. One set, V V' V'' V''' V'', project equidistant from the periphery of the wheel, and the other set, V' V'' V''' V'' V'', project equidistant from the right-hand side of the wheel T. The line which 85 connects each spur of each set with the axis of the wheel T is half-way between the lines which connect the two adjacent spurs of the other set with that axis.

T' is a gear keyed to the shaft U.

90

A' is a gear keyed to the end of the tube B'. The gear T' bears to the gear A' the proportion of five to twelve. The tube B' revolves with a running fit around the shaft R. To the left-hand end of the latter shaft the minute-wheel C' is keyed, and to the left-hand end of the tube B' the hour-wheel D'' is keyed. The hour-wheel has the figures 1 to 12, inclusive, raised upon its periphery at equal distances apart, and the minute-wheel has the figures 95 05, 10, 15, 20, 25, 30, 35, 40, 45, 50, 55, 00, similarly raised upon its periphery. Upon the 100

periphery of the wheel Q similar figures to those last enumerated are raised or sunk or otherwise affixed, and the figures 1 to 12, inclusive, are raised or sunk or otherwise fixed upon the outer surface of twelve equidistant teeth of the gear A', respectively. The two sets of figures on the wheels Q and A' are arranged in the same direction and order with those on the minute and hour wheels, respectively, but six numbers in advance of the latter, so that the uppermost figures on the wheels Q and A' will always correspond with the undermost figures on the minute and hour wheels, respectively. So, also, the figures on the wheels Q and A' are direct in form, while those on the minute and hour wheels are inverted, as printers' type are. Manually-changed matter may be inserted in the border of the surface of the stamp proper in any suitable manner.

The mode of operation of this apparatus is as follows: A chronometer outside of the apparatus is so connected with the shaft F that the latter revolves and causes the gear G and the wheel H to revolve continuously, and to make one revolution every half-hour in the direction shown by the arrow adjacent to the wheel H in Fig. 3. That revolution strains the spiral spring N, through the action of the gear M; and it also soon brings the spur K opposite the nearest opening in the discontinuous flange of the wheel H. Thereupon, the spring N, operating upon the gear I, forces the latter to revolve, and the spur K to escape through that opening; but thereupon the spur K' instantly comes in contact with the outside of the discontinuous flange of the wheel H, and thus arrests the revolution of the gear I when it has passed over one-sixth of its circumference. Five minutes later the spur K' escapes through an opening of the discontinuous flange, but is thereupon instantly arrested by coming in contact with the inner side of that flange on the opposite side of the wheel H, after passing through one-sixth of its circle. Thus, through the action of the gears M and G and the spring N and the wheel H, the continuous rotary motion of the shaft F is translated into an intermittent rotary motion of one revolution (every half-hour) of the gear I, the shaft J, and the ratchet O, that intermittent motion taking place every five minutes, and carrying each of the three parts last named through one-sixth of its circumference. The gear I causes the wheel Q, the shaft R, and the minute-wheel C' to revolve once every hour with twelve equal intermittent motions in the direction shown by the arrows adjacent to the wheel Q in Figs. 3 and 6. Every twelfth of the twelve intermittent motions of the wheel Q causes the gear A', the tube B', and the hour-wheel D' to revolve one-twelfth of their respective circumferences by means of the wheel T and the gear T' operating as follows: The end of the eleventh motion of the wheel Q, having

brought the spur Q' nearly into contact with the spur V, the twelfth motion causes the former spur to strike the latter, and thus forces the wheel T to revolve and carry the spur V⁵ into the recess S. The wheel Q, continuing to revolve, the recess S carries the spur V⁵ to the position just vacated by the spur V⁶, and will then eject the spur V⁵, and will pass a little beyond it. This operation thus results in causing the wheel T to revolve one-fifth of its circumference, and to lock it in its new position by means of the spurs V⁵ and V⁶ bearing against the periphery of the wheel Q till the latter wheel makes its twelfth succeeding motion. The gear T' being keyed to the same shaft with the wheel T, and being proportioned to the gear A' as five is to twelve, will give the latter an intermittent motion of one-twelfth of its circumference whenever the wheel T moves through one-fifth of its circumference. The result of the operation thus far explained is to make the minute-wheel C' change its presented figures every five minutes, and to make the hour-wheel D' do likewise every hour. The stamping-surfaces being furnished with ink in any proper manner, and the apparatus being so set that the undermost figures on the hour and minute wheels correspond with the time of setting, and the wheel H being so adjusted to the gear I that the first escapement will occur exactly five minutes thereafter, it is clear that figures representing the hour and minute, together with any fixed or manually-changeable characters in the face of the stamp will be stamped upon any paper placed beneath the stamping-surface as often as the handle E'' is depressed. Should that handle be depressed at any instant whereon an escapement is occurring, the blade P, instead of being idle as at other times, would strike against one of the projections of the ratchet O, and would thus force the ratchet and with it the gear I back to the position they occupied before the escapement began to occur, and would hold them in that position till the impression is made and the handle released, and the frame C forced upward by the springs E E'. Thereupon the delayed escapement would occur, and succeeding escapements would take place at their appointed times, provided the handle E'' is not held down by the user unnecessarily long.

The figures on the wheels Q and A' are placed there to enable the user to set the printing-wheels to any given time without the inconvenience of examining their presented figures or taking an impression thereof, in order to ascertain which set are downward at the time in which the setting is being done.

The teeth of the gear I and of the wheel Q may have their outer edges curved convexly; but the angle shown in the drawings between the peripheries of the two is so small that no such curving is absolutely required. So, also, the journals D D' may be either above or below the common tangent of the gear I and the

wheel Q, in which case one or both of the latter should be made wide in peripheral surface, so as to permit of the resulting longitudinal motion of the lower part of the periphery of the wheel Q. If but one printing-wheel is required, the wheel T, the gear T', the gear A', the tube B', and the wheel D" may all be omitted, and the wheel Q, constructed as a gear without the left-hand part shown in the drawings.

I do not herein claim an escapement consisting of a wheel provided with a series of studs, and of another wheel provided with a discontinuous flange; nor an intermittent lock motion consisting of a wheel provided with a stud and a recess, and of another wheel provided with two series of studs, though both those inventions are shown in this specification, because both are claimed in my application No. 93,662 for Letters Patent for an improvement in time-stamps, filed May 2, 1883.

I claim as my invention—

1. The combination of the frame A, the frame C, pivoted in frame A, the gear I, the wheel Q, the shaft R, and the wheel C. 25

2. The combination of the frame A, the frame C, pivoted to the frame A, the gear I, the wheel Q, the shaft R, the wheel C', the wheel T, the shaft U, the gear T', the gear A', the tube B', and the wheel D". 30

3. The combination of the shaft F, the gear G, the wheel H, the shaft L, the gear M, the spring N, and the gear I.

4. The combination of the frame A, the frame C, pivoted to the frame A, the blade P, 35 the ratchet O, the shaft J, the gear I, the wheel Q, and the shaft R.

WILLIAM H. GILLETTE.
